ATTORNEY.

UNITED STATES PATENT OFFICE

WILLIAM G. GOODWIN, OF ROYAL OAK, MICHIGAN

CASTING

Application filed September 10, 1928. Serial No. 304,959.

My invention relates to a new and useful improvement in a casting and particularly a casting in which it is desired that there be effective radiation. The invention lends itself particularly to the formation of engine cylinders, steam radiators, air compressors and other types of machinery in which heat is generated and in which a rapid radiation of the heat is desired. It is the object of the 5 present invention to provide a casting of this class, so arranged and constructed, as to effect rapid radiation.

It is another object of the present invention to provide a casting having a plurality 15 of outwardly projecting heat conducting members mounting therein and preferably formed integral therein.

It is another object of the invention to provide a casting having formed integral therewith 20 heat conducting parts formed from material of a thermal conductivity higher than the main body itself.

Other objects will appear hereinafter.

The invention consists in the combination 25 and arrangement of parts hereinafter described and claimed.

The invention will be best understood from a reference to the accompanying drawings which form a part of this specification and in 30 which,

Fig. 1 is a side elevational view of them with parts broken away and parts shown in section.

Fig. 2 is a sectional view taken on line 2—2 35 of Fig. 1.

Fig. 3 is a perspective view of the radiator fin used in the invention.

In the drawings, I have illustrated the invention applied to an engine cylinder 7. This 40 cylinder 7 is from the cast metal and rings 8 tapered to an outer edge are embedded in the casting 7, the metal being cast about the rings. These rings are formed from metal of a higher thermal conductivity than the 45 casting 7 such as copper or the like so as to afford a rapid conduction of the heat.

With a casting formed in this manner, a cooling of the casting is effected to a high degree and an efficient operation of the engine 50 assured.

While I have illustrated and described the preferred form of construction, I do not wish to limit rights to the precise details of structure shown but desire to avail myself of such variations and modifications as come within 55 the scope of the appended claim.

Having thus described my invention, what I claim as new and desire to secure by Letters Patent is:

A casting of the class described, comprising: a main body having an inner and an outer surface, the outer surface being free from outwardly extending projections; a plurality of radiating members projecting outwardly from the outer surface of said main body and extending inwardly of said main body and terminating between the inner surface and the outer surface thereof, the portion of each of said members within said casting being of greater volume in proportion 70 to radial length relative to said casting than the portion exterior of said casting.

In testimony whereof I have signed the foregoing specification.

WILLIAM G. GOODWIN. 75
